OVEN WALL CONSTRUCTION

Charles L. Gehnrich, Elmhurst, N. Y.

Application June 16, 1939, Serial No. 279,483

1 Claim. (Cl. 189—1)

This invention relates to industrial ovens and more particularly to ovens having sectional built-up walls.

An object of the invention is to provide a construction in which a minimum amount of heat transfer takes place through the oven walls.

Another object is to provide an oven wall having no through metal, that is, having no continuous metal parts extending entirely through the wall.

Another object is to provide an efficient, dependable oven wall construction which may be easily assembled and may be built up to any desired size.

Various other objects and advantages will be apparent as the nature of the invention is more fully disclosed.

The invention may be better understood by referring to the following description, taken in connection with the accompanying drawings, in which a specific embodiment thereof has been set forth for purposes of illustration.

In the drawings:

Fig. 1 is a broken horizontal section through an oven wall embodying the present invention;

Fig. 2 is a vertical section taken along the line 2—2 of Fig. 1;

Fig. 3 is a broken side elevation of the oven wall;

Fig. 4 is an enlarged detail view showing the corner construction; and

Fig. 5 is a partial perspective view showing the construction of one of the top plates.

Referring to the drawings more in detail, the oven wall is shown as of three-ply construction, comprising an inner ply 10, an intermediate ply 11 and an outer ply 12. Each of said plies is built up from a plurality of panels which are assembled to form a substantially continuous wall. In accordance with the present invention, the various plies are held together in the manner to be described and without the use of any through metal which would be capable of transferring heat through the oven walls.

The inner ply 10 is formed of a plurality of panels 14, each of which may comprise a body of heat insulating material having an inner metallic facing 15. The facing 15 is shown as extending around the ends of the insulating material 14 to form a tongue 16 at one end and a groove 17 at the opposite end, the tongue and groove being shaped and dimensioned to receive the corresponding elements of adjacent panels. Each panel preferably extends from the top to the bottom of the oven, the construction being

such that the oven may be built up to any desired length by joining a plurality of such panels together.

Referring to Fig. 1, it will be noted that the corner panels 18 are of similar construction except that they are bent at right angles so as to form a closed corner.

The intermediate ply 11 is shown as comprising a layer of sheet insulating material which may be formed in a plurality of panels 19, each of which preferably extends from the top to the bottom of the oven. The ply 11 may also be built up to any desired length by use of the required number of panels.

The outer ply 12 comprises a plurality of panels 20 which are of similar construction to the panels 14, above mentioned, and may comprise a layer of heat insulating material 21 provided with an outer facing 22 of metal which may be bent around the opposite edges to form tongues 23 and grooves 24.

The panels above described are assembled on a base or bottom member 30, preferably of metal, having outer flanges 31 and inner flanges 32. The flanges 32 may be secured to the member 30 in any convenient manner and, with the flanges 31, form channels extending around the sides and back to receive the upright side and back wall sections. It is to be understood that the front wall is formed by suitable doors, not shown.

The side and back walls are each formed of the inner, intermediate and outer plies, above mentioned, which are built up to a length corresponding to the oven dimensions and are positioned in the channels formed between the flanges 31 and 32. A top plate 35 (Fig. 5) is positioned over the top of the inner wall panels 14. This plate 35 may be of a suitable length to span a plurality of panels and may, if desired, be made of a length corresponding to that of the oven. The plate may be formed from a single sheet of metal which may be bent to provide an inner horizontal flange 36 and a channel 37 adapted to extend over and frictionally engage the top portions of the various panels. An outer vertical flange 38 may be formed adjacent the channel 37 to provide a shoulder against which the top panel of the oven may be positioned in the manner to be described. The outer wall panels 20 may be provided with a channel-shaped top plate 40 which may extend over a plurality of such panels in a manner similar to the top plate 35 so as to firmly secure the panels together.

After the side walls of the oven have been assembled, as described above, with the top plates 35

35 and 40 in position and with the intermediate ply 11 forming a complete heat insulating blanket between the inner and outer plies, the top may be assembled in the following manner:

5 The top wall of the oven is built up of inner panels 45, intermediate panels 46 and outer panels 47 which are similar in construction to the corresponding panels of the side walls. These top panels preferably extend across the entire 10 width of the oven, but are built up to the length of the oven by positioning successive panels end to end in the manner described in connection with the side walls. The inner top panel 45 is positioned on the top plate 35 with its ends engaging the vertical flange 38 thereof. The intermediate panel 46 is positioned over the inner panel 45 and extends over the top ends of the intermediate panels 11 of the side walls. The outer panel 47 is positioned on the intermediate 15 panel 46 and is fitted between the top plates 40 of the outer panels 20 of the side walls.

20 After the oven has been built up in this manner, horizontal and vertical corner pieces 50 and 51 respectively are brought into position and are 25 clamped by suitable tie-rods 52 which complete the assembly and form a firm, rigid unit.

25 It is to be noted that in the above construction the intermediate ply 11 extends entirely around the sides, back and top of the oven and forms 30 a continuous heat insulating blanket between the inner and outer wall panels. The inner and outer plies are each formed of a plurality of panels which are dove-tailed together and built up to the required oven length and are held in a firm 35 unit without the use of through-bolts or other metallic members which could conduct heat through the oven walls. The construction, furthermore, permits the efficient use of various heat insulating materials. The inner wall panels, 40 for example, are subjected to the high temperatures of the oven and require a heat insulating material of a relatively high grade. The inner metal facing 15 must also be of a suitable material to withstand the high temperatures of the 45 oven. The intermediate ply, being shielded from the intense heat of the oven by the inner wall panels, may be of a lower grade heat insulating

material, and the outer panels, which are subjected to only a relatively low temperature, may be made of a still lower grade heat insulating material. In this way the oven may be economically constructed with the use of materials, each of which is best adapted for its particular function. The outer facing 22, of course, need not be made of heat resisting metal, but may be made of any material capable of withstanding the conditions to which it is subjected.

5 It is to be understood, of course, that, in the case of comparatively small ovens, each of the wall sections may comprise only a single panel, in which case outer tie-rods located at the front and rear corners of the oven may provide a 15 sufficient support for the entire furnace. If the oven is built up of a plurality of panels, it may be desirable to provide a plurality of such supports spaced along the sides thereof.

20 Although a specific embodiment has been shown for purposes of illustration, it is to be understood that various changes and modifications may be made therein as will readily appear to a person skilled in the art. The invention is only to be limited in accordance with the scope 25 of the following claim.

I claim:

25 An oven, comprising walls formed of inner, intermediate and outer plies, said inner and outer plies each comprising a plurality of panels, each of said panels comprising a body of heat insulating material and a metal facing on the exposed side, said metal facing extending around the opposite ends of said panels to form tongues and grooves respectively, adjacent channels being 30 joined together by said tongues and grooves to form a substantially continuous ply, said intermediate ply consisting entirely of panels of heat insulating material and forming a complete heat insulating blanket between said inner and outer plies without metallic members extending there-through, horizontal and vertical corner pieces at the various corners of said oven and top tie-bolts on the outside of the oven engaging said corner pieces to hold the oven as a firm rigid unit.

40 45 CHARLES L. GEHNRICH.
